Related U.S. Application Data

(60) Division of application No. 29/422,890, filed on May 24, 2012, which is a division of application No. 29/324,385, filed on Sep. 11, 2008, which is a continuation-in-part of application No. 29/305,208, filed on Mar. 14, 2008, now Pat. No. Des. 585,111.

Primary Examiner — T. Chase Nelson(51) **LOC (9) Cl. .... 23-01***Assistant Examiner* — Mark Cavanna(52) **U.S. Cl.**(74) *Attorney, Agent, or Firm* — Foley & Lardner LLPUSPC ..... **D23/243; D23/263****CLAIM**(58) **Field of Classification Search**

I claim the ornamental design for a plumbing fitting, as shown and described.

USPC .. D23/200, 238-257, 259, 263, 266; D6/512, D6/546, 550; D8/300, 307-308, 310-312, D8/321; 4/675-678; 137/801, 599.01; 16/110.1, 16/441

DESCRIPTION

See application file for complete search history.

FIG. 1 is a right, top, front perspective view of a plumbing fitting according to an embodiment of my new design; FIG. 2 is a right side elevational view thereof; FIG. 3 is a left side elevational view thereof; FIG. 4 is a front elevational view thereof, the rear elevational view thereof being a mirror image of the front view shown; FIG. 5 is a top plan view thereof; and, FIG. 6 is a bottom plan view thereof.

(56) **References Cited**

The broken lines in the drawings are for purposes of illustrating portions of the plumbing fitting that form no part of the claimed design.

U.S. PATENT DOCUMENTS

The broken away symbols in the drawings indicate the appearance of any portion of the article between the break lines forms no part of the claimed design.
